UNITED STATES PATENT OFFICE.

JOHN S. BARNES, OF ROCKFORD, ILLINOIS, ASSIGNOR TO W. F. & JOHN BARNES COMPANY, OF ROCKFORD, ILLINOIS, A CORPORATION OF ILLINOIS.

AUTOMATIC FEED MECHANISM AND STOP FOR DRILLING MACHINES.

Application filed April 18, 1921. Serial No. 462,416.

To all whom it may concern:

Be it known that I, JOHN S. BARNES, a citizen of the United States, residing at Rockford, in the county of Winnebago and

- 5 State of Illinois, have invented certain new and useful Improvements in Automatic Feed Mechanism and Stops for Drilling Machines, of which the following is a specification.
- 10 This invention pertains in general to the art of drilling machines, and has more particular reference to feed mechanisms therefor, and to an automatic stop; although it will be apparent as the invention becomes
- 15 better understood that my invention is generally applicable to any machine tool in which a tool spindle or the like is moved by a feed mechanism, and in which it is desired to automatically stop the feed at a prede-
- 20 termined point.

The primary object of the present invention is to provide a feed mechanism and automatic stop of generally improved and novel construction, with a view to simplicity, 25 compactness, precision in operation, wide range of adjustment, and economy in production.

In furtherance of the foregoing I have aimed to provide in connection with a drilling machine, a feed shaft directly associated with the tool spindle and carrying a member having a spiral groove, and the further provision of an adjustable abutment on said member adapted to actuate a follower 35 in said groove, to thereby discontinue the feed of said shaft.

Other objects and attendant advantages will be appreciated by those familiar with this art as the invention becomes better understood by reference to the following description when considered in connection with the accompanying drawings, in which—

Figure 1 is a side elevation of the upper 45 portion of a drilling machine embodying my invention;

Fig. 2, a front elevation of the part shown in Fig. 1;

Fig. 3, an enlarged horizontal sectional 50 view taken substantially on the line 3—3 of Fig. 2;

Fig. 4, a sectional view taken substantially on the line 4—4 of Fig. 3; and

Figs. 5 and 6, detail sectional views taken on the lines 5—5 and 6—6, respectively, of Fig. 4.

In the drawings, I have illustrated only such parts of a drilling machine as are necessary for an understanding of the present invention. A frame designated generally by character 8, carries suitable bearings 9 and 11, in which a tool spindle 12 is rotatable and slidable axially. The spindle is moved vertically through the usual sleeve 13 and slidable in the bearing 11, and has a suitable thrust bearing 14 at its upper end with the spindle. This sleeve carries a rack 15 with which meshes a pinion 16 fixed to a feed shaft 17 adapted to be operated by feed mechanism which will presently be described.

Any suitable means may be employed for driving the spindle, such for example as a drive shaft 18, equipped with the usual cone pulley 19 and connected to the spindle through the agency of bevel gears 21. In the present example, the drive to the feed shaft 17 is transmitted from the driving shaft 18 through the intermediary of a change speed device, although this is not essential to the invention, as it will be readily appreciated that as regards the automatic stop mechanism which will be described later, the feed shaft thereof may be driven by any suitable means. In the present instance the bevel gear 21 on the spindle is fixed to a spiral tooth-gear 22 with which meshes a complementary gear 23, fixed to a shaft 24 revolvably supported in suitable bearings on the frame. A gear 25 splined on the shaft 24 is adapted to be shifted lengthwise thereon by means of a hand shifter 26 for engaging the gear 25 in any of a plurality of concentric gear teeth on the gear wheel 27. It will be readily seen that by shifting the member 26, any of a plurality of speeds may be imparted to the shaft 28 to which the gear 27 is fixed.

A housing 29 supported for oscillation on the shaft 28 provides an upper bearing for the vertical shaft 31, which is splined to a spiral-tooth gear 32 within said hous-

ing. The gear 32 meshes with a similar gear 33, fixed to the shaft 28. The shaft 31 carries at its lower end a housing 34 and a fixed worm 35 within such housing. 5 This worm is adapted to mesh with a worm gear 36 fixed to the feed shaft 17. The end thrust of the worm up and down, will be taken by the housing 34 and the shaft 51, mentioned hereinafter. The worm housing 10 34 is shaped to provide a forwardly extending oil basin 30 adapted to carry a sufficient quantity of oil to insure self-lubrication for the worm and gear for a long period. By means of a hand wheel 37 fixed 15 to the lower end of the shaft 31, the worm 35 may be turned by hand for feeding the spindle. To permit this hand feed, it is of course, necessary to shift the member 26 to a neutral position, in which the 20 gears 25 and 27 are disconnected. The feed shaft may also be revolved by the usual hand feed.

Upon the end of the feed shaft opposite its driven end, is fixed a circular member 25 39 shaped on its inner face to provide a spiral groove 41 the convolutions of which lead outwardly in a clock wise direction viewing Fig. 4. A follower 42 disposed in said groove is pivotally supported at 43 30 upon the outer end of a sectional lever, designated generally by character 44, so that the follower is free to swing radially as the member 39 revolves. A suitable abutment 45, adapted to be set at any position 35 throughout the length of the spiral groove and to be secured in such position by means of a set screw 46, will impinge the top of the follower 42 when the latter is reached by rotation of the member 39 in a counter-clockwise direction, viewing Fig. 4. The hand lever 44, formed in two sections 47 and 48 pivotally connected together at 49, is 40 fixed to a shaft 51, supported on the main frame. This shaft is connected through 45 means of an arm 52, to the housing 34 as shown plainly in Fig. 1, so that by oscillation of the lever the worm 35 will be moved into and out of mesh with the worm gear 36. The lever sections 47 and 48, have de- 50 pending lugs 52 and 53 respectively, between which is interposed a coil spring 54, which constantly urges the lever sections 47 in a clockwise direction into the position shown in Fig. 4, which is limited by a stop 55 striking an abutment 56 on the lever section 48. The lever is supported in this normal position by reason of the lug 52 resting in a notch 57 formed in the frame portion 58. It will be manifest from the fore- 60 going that the lever 44 is normally supported by a device adapted to be tripped for allowing the lever to fall, and thereby disengage the feed. The trip is effected by 65 the abutment 45 striking the follower 42, thereby swinging the lever section 47 in a

counter-clockwise direction about the pivot 49 and against the pressure of the spring 54 until the lower end of the lug 52 is withdrawn from the recess 57, allowing the lever to fall.

Operation of any of three means are available for imparting feed motion to the spindle. A rapid and sensitive feed is obtained by the hand lever 38. A slow feed, generally of short duration as for facing, is obtained by operation of the hand wheel 37. Power feed at any of the speeds determined by the position of the shifter 26 is obtained when the lever 44 is raised to the operative position shown in full lines in the drawings. The duration of this feed depends on the position of the abutment 45 in the groove 41. In the position of the parts shown in Figs. 1 and 4, the spindle has been fed down a trifle over half of its feed movement by rotation of the feed shaft 17 in a counter clock wise direction. Upon continuing such movement of the feed shaft another half revolution the abutment 45 will strike the top of the follower 42, thereby tripping the lever 44 as above mentioned and disconnecting the power feed. The follower swings on its pivot 43 so that the end 42 located in the spiral groove moves radially as the member 39 revolves, the term "radially" being used herein and in the claims as meaning outwardly and inwardly with respect to the center of said member, such movement being incidental to following the convolutions of the spiral groove or guide. By either advancing or retracting the position of the abutment 45 the feed will obviously be of a shorter or longer duration and, inasmuch as the length of the spiral groove is proportional to the total length of the feed, it will be manifest that by setting the abutment 45 at any point in said groove between the outer end thereof and the follower, the feed may be stopped at any predetermined point. Said groove in the present instance has three complete convolutions comprising approximately 1080 degrees in which the abutment may be set for stopping the feed. Since this comparatively large number of degrees comprises the total feed of the spindle or tool carrier the feed may be stopped at any point within its high and low limits, with but a single setting of the stop or trip abutment 45. This is distinguished from prior constructions wherein but a single annular groove is employed allowing setting of a stop or trip member only within approximately 360 degrees. Consequently the present invention enables a greater range of feed control and greater accuracy in stopping the feed.

It is believed that the foregoing conveys a clear understanding of the principles and objects of this invention, and while I have

illustrated and described but a single working embodiment thereof, it should be understood that various changes might be made in the construction and arrangement without departing from the spirit and scope of the invention as expressed in the appended claims, in which—

I claim:

1. In a drilling machine, the combination of a drill spindle, a feed shaft therefor, a worm gear and a worm for revolving the feed shaft, a member on said shaft having a spiral groove longer than a single convolution and corresponding in length to approximately the total spindle feed, an abutment adjustable to any point in said groove, a follower in said groove adapted to be operated by said abutment, and means actuated by said follower for disconnecting the worm and gear.

2. The combination of a tool spindle, a feed shaft for said spindle, driving mechanism for revolving said shaft, a member driven by said shaft and having a spiral groove longer than a single convolution and corresponding in length to approximately the total spindle feed, an abutment adapted to be secured at any position throughout the length of said groove, a follower in said groove adapted to be actuated by said abutment, and means actuated by said follower for disconnecting said driving mechanism from the feed shaft.

3. An automatic feed and stop mechanism for drilling machines comprising in combination, a drill spindle, a feed shaft therefor, means for driving the feed shaft, a member on said feed shaft having a spiral groove of a length corresponding to the total spindle feed, a follower disposed in said groove and movable radially of said member as the latter is revolved, an abutment adapted to be set at any point in said groove for actuating said follower, and means operated by said follower for causing the driving means to be disconnected from the feed shaft.

4. The combination of a tool spindle, a feed shaft therefor, a worm gear on said shaft, a worm movable into and out of mesh with said gear, a member on said shaft having a spiral groove of a length corresponding to the total spindle feed, means for disconnecting said worm from the gear including a follower disposed in said spiral groove and movable radially by rotation of the grooved member, and an abutment adjustable to any of various positions in the groove for actuating said follower and thereby causing the worm to be disconnected at a predetermined point in the feed.

5. In a drill press, the combination of a drill spindle having a sleeve and rack, a feed shaft equipped with a pinion meshing with said rack, a worm gear fixed to the feed shaft, a driving worm adapted to be moved

into and out of mesh with the worm gear, means on said feed shaft having a spiral guide of greater length than a single convolution and being determinative of the length of the spindle feed, a follower associated with said guide, adjustable means in connection with the spiral guide for actuating the follower, and a trip device adapted to be actuated by said follower for causing the worm to be disengaged from the worm gear.

6. In a drilling machine, the combination of a drill spindle, a feed shaft therefor, means for driving said shaft, a member on the feed shaft having a spiral groove of a length corresponding to the total spindle feed, a lever supported in a normal position by a trip device and equipped with a follower disposed in said groove, means adjustable to a set position on said member at any point within the length of said groove for actuating the follower to trip the lever, and means operated by the lever when so tripped for disconnecting the driving means from the feed shaft.

7. In a drilling machine, the combination of a drill spindle, a feed shaft therefor, a worm gear on the feed shaft, a driving shaft equipped with a worm meshing with said worm gear and also equipped with a hand wheel, whereby the spindle may be fed by hand, a member on the feed shaft having a spiral groove of a length corresponding to the total spindle feed, a follower disposed in said groove and adapted to be actuated by an abutment carried by said member, and means put into operation by actuation of said follower for disconnecting the worm from the worm gear.

8. In a machine tool, a feed and stop mechanism comprising, in combination, a tool carrier, a rack moving with the tool carrier, a pinion meshing with the rack for imparting feed movement to the tool carrier, mechanism for revolving the pinion adapted to be disconnected, means rotating with the pinion having a spiral guide of a length corresponding to the total spindle feed, and means adapted to be set at any predetermined position throughout the length of said guide for disconnecting said mechanism.

9. In a machine tool, a feed and stop mechanism comprising, in combination, a tool carrier, mechanism for imparting feed movement to said carrier adapted to be disconnected for stopping the feed, and means for disconnecting said mechanism including a spiral guide of a length corresponding to the total spindle feed, said guide being connected to revolve with the feed-transmitting mechanism, and means adapted to be set within the length of said guide for disconnecting said mechanism at a predetermined point in the travel of the tool carrier.

10. In a machine tool, a feed and stop

mechanism comprising, in combination, a tool carrier, mechanism for imparting feed movement thereto, and means for stopping said feed at a predetermined point in the travel of the tool carrier including a spiral guide of a length corresponding to the total spindle feed, connected to revolve simultaneously with travel of the tool carrier, and means adapted to be set within the length of said spiral guide for stopping the feed.

11. In a drilling machine, in combination, a tool spindle, means for imparting feed movement to said spindle including a rotary part adapted to make plural complete revolutions to transmit the total spindle feed, and mechanism for rotating said feed-transmitting part and for automatically stopping the feed including a spiral guide rotating with said part and being of a length corre-

sponding to the total feed length of the spindle and means adapted to be set at any position in the length of said spiral guide for stopping the feed at a corresponding point in the travel of the spindle.

12. In a drilling machine, in combination, a tool spindle, a rack for imparting feed movement to the spindle, a pinion meshing with the rack, feed mechanism for rotating the pinion, and automatic feed stop mechanism including a part rotating with the pinion and having a spiral groove corresponding in length to the total feed length of the spindle, and means adapted to be set at any point in the length of the spiral groove for automatically stopping said feed movement at a corresponding point in the travel of the spindle.

JOHN S. BARNES.
